HANDLED CUP OR LIKE RECEPTACLE

Kenneth T. Butterly and Louis W. Sutherland,
Jr., Kalamazoo, Mich., assignors to Sutherland
Paper Company, Kalamazoo, Mich., a corpora-
tion of Michigan

Application April 16, 1947, Serial No. 741,855

6 Claims. (Cl. 229—4:5)

1

This invention relates to improvements in handled cups or like receptacles.

The present invention is an improvement upon and an adaptation of the structure of the Annen Patent 2,060,781, issued November 17, 1936.

The main objects of this invention are:

First, to provide a handled cup or receptacle in which the handle may be collapsed against the side of the cup or receptacle to permit nesting or swung to erected position or position for grasping and effectively supported in erected position.

Second, to provide a handled receptacle having these advantages which is very simple in structure and requires no additional stock to provide the feature of maintaining the handle members in erected position.

Objects relating to details and economies of the invention will appear from the description to follow. The invention is defined and pointed out in the claims.

Preferred embodiments of the invention are illustrated in the accompanying drawing, in which:

Fig. 1 is a perspective view of a cup type of receptacle embodying the invention with the handle members in erected position.

Fig. 2 is a horizontal section on a line corresponding to line 2—2 of Fig. 1.

Fig. 3 is a plan view of the blank from which the body or side wall of the container is formed.

Fig. 4 is a fragmentary view of a blank of a modified form or embodiment of the invention.

Fig. 5 is a fragmentary view of the modified form or embodiment of the invention shown in Fig. 4 with the handle members erected.

In the embodiment of the invention illustrated the body or wall 1 of the receptacle is formed of a blank 2 of sheet paper or container stock terminating at one end in the sealing flap 3 which is overlapped and adhesively secured to the other end 4. This blank is provided with a bottom securing extension or flap 5, the bottom not being illustrated as it forms no part of the present invention. It may be that shown in the Annen patent referred to.

The overlapping sealing portion of the flap is conformed and slit to provide handle members 6 and 7 normally collapsed against the side of the receptacle but hinged at 8 to permit their being swung to erected position as shown in Figs. 1 and 2. The handle members shown in the embodiment of Figs. 1, 2 and 3 do not have a central opening designed to receive the finger.

The sealing flap and handle members are pro-

2

vided with U-shaped slits 9 partially in the sealing flap itself and extending beyond the hinge connections 8 for the handle members into the handles, the arms of these slits being desirably converged outwardly.

This provides tongue-like strut members 10 which are bendable or deflectable on their connections 11 to the handle members so that while these tongue-like struts lie in the general plane of the handle members when the handle members are collapsed they may be swung outwardly to bracing or strut engagement with the side walls of the receptacle as is shown in Fig. 2 thereby supporting the handle members in erected position.

It will be understood that the handle members are simultaneously grasped and when grasped are brought together in side by side relation—that is, the outer portions are in side by side relation but when the flap is released the handle members are maintained in the outwardly projecting erected position so that they may be again grasped very easily.

In the embodiment of the invention shown in Figs. 4 and 5 the handle members 111 and 12 are of U-shape, portions thereof being cut out to provide finger openings 13. In this embodiment, the tongue-like supporting lugs 14 are cut from the sealing flap so that they extend from the hinged ends 15 of the handle and they are relatively short so that when the handle members are erected these strut tongues swing outwardly to bracing position as is shown in Fig. 5, thereby maintaining the handle members in erected position or in convenient position for grasping.

The handled receptacles of the invention may be economically produced as there is no additional stock required over the handle receptacle shown in the Annen patent referred to.

We have illustrated and described very practical embodiments of the invention. We have not attempted to illustrate or describe other embodiments or adaptations as we believe this disclosure will enable those skilled in the art to embody or adapt the invention as may be desired.

Having described our invention, what we claim as new and desire to secure by Letters Patent is:

1. A receptacle comprising a side wall formed of a blank having a body portion terminating at one end in a sealing flap conformed at its end and slitted to provide oppositely disposed handle members, said handle members having hinge connections to the sealing flap, the sealing

flap being lapped upon the outside of the other end of the body portion and adhesively secured thereto to permit the handle members being swung outwardly to erected position, the sealing flap and handle members being slit to provide struts hingedly connected at their outer ends to the handle members and lying normally in the plane of the handle members when they are collapsed with the inner ends of the struts extending beyond said hinge connections on the side thereof opposite from the handle members, the struts being deflectable outwardly to a bracing position in which the struts engage the sides of the receptacle for maintaining the handle members in erected position.

2. A receptacle comprising a side wall formed of a blank having a body portion terminating at one end in a sealing flap conformed at its end and slitted to provide oppositely disposed handle members, said handle members having hinge connections to the sealing flap, the sealing flap being lapped upon the outside of the other end of the body portion and adhesively secured thereto to permit the handle members being swung outwardly to erected position, the handle members having integral struts partially severed therefrom and deflectably connected thereto adjacent the hinge connections of the handle members to the sealing flap, the struts being deflectable outwardly to a bracing position in which the struts engage the sides of the receptacle for maintaining the handle members in erected position.

3. A receptacle comprising a side wall formed of fibrous sheet material and having handle members integral therewith, said handle members having hinge connections to said side wall and being collapsible oppositely against the outer side thereof and swingable outwardly to erected position, the handle members having pairs of deflectable strut members projecting beyond said hinge connections on the sides thereof opposite from the handles and adapted when the handle members are swung to their erected position to be adjusted outwardly to bracing position against the outer side of the receptacle for maintaining the handle members in erected position.

4. A receptacle comprising a side wall formed of fibrous sheet material and having handle members integral therewith, said handle members having hinge connections to said side wall

and being collapsible oppositely against the outer side thereof and swingable outwardly to erected position, the handle members having deflectable strut members projecting beyond said hinge connections on the sides thereof opposite from the handles and adapted when the handle members are swung to erected position to be adjusted outwardly to bracing position against the outer side of the receptacle for maintaining the handle members in erected position.

5. A receptacle comprising a side wall formed of fibrous sheet material and having integral handle members, said handle members having hinge connections to the side wall and being collapsible oppositely against the outer side thereof and swingable outwardly to erected position, the handle members being of inwardly facing U-shape and hingedly connected at both sides of their openings which constitute finger openings, 15 and pairs of handle support members extending beyond said hinge connections on the sides thereof opposite from the handle members and adjustable outwardly when the handle members are erected to a bracing position against the side of the receptacle for maintaining them in erected position.

6. A receptacle comprising a side wall formed of fibrous sheet material and having integral handle members, said handle members having hinge connections to the side wall and being collapsible oppositely against the outer side thereof and swingable outwardly to erected position, and handle support members extending beyond said hinge connections on the sides thereof opposite from the handle members and adjustable outwardly when the handle members are erected to a bracing position against the side of the receptacle for maintaining them in erected position.
